(57) **CLAIM**

The ornamental design for a plurality of strips of kinesiology tape with an X-shaped configuration, as shown and described.

DESCRIPTION

FIG. 1 is an upper view of a plurality of strips of kinesiology tape with an X-shaped configuration;

FIG. 2 is a top view of the plurality of strips of kinesiology tape with an X-shaped configuration;

FIG. 3 is a bottom view of the plurality of strips of kinesiology tape with an X-shaped configuration;

FIG. 4 is a left side view of plurality of strips of kinesiology tape with an X-shaped configuration;

FIG. 5 is a right side view of the plurality of strips of kinesiology tape with an X-shaped configuration;

FIG. 6 is a front view of the plurality of strips of kinesiology tape with an X-shaped configuration; and,

FIG. 7 is a rear view of the plurality of strips of kinesiology tape with an X-shaped configuration.

The broken line showing illustrates a portion of the design that forms no part of the claimed design.

1 Claim, 4 Drawing Sheets
